CLAIM

The ornamental design for a reducer with a crimped end, as shown and described.

DESCRIPTION

FIG. 1 is a front elevational view of a first embodiment of the reducer with a crimped end; the rear elevational, top and bottom views being identical to FIG. 1;

FIG. 2 is a front perspective view of the reducer of FIG. 1;

FIG. 3 is a left end view of the reducer of FIG. 1;

FIG. 4 is a right end view of the reducer of FIG. 1;

FIG. 5 is a front elevational view of a second embodiment of the reducer with a crimped end; the rear elevational, top and bottom views being identical to FIG. 5;

FIG. 6 is a front perspective view of the reducer of FIG. 5;

FIG. 7 is a left end view of the reducer of FIG. 5;

FIG. 8 is a right end view of the reducer of FIG. 5;

FIG. 9 is a front elevational view of a third embodiment of the reducer with a crimped end; the rear elevational view being a mirror image of FIG. 9;

FIG. 10 is a front perspective view of the reducer of FIG. 9;

FIG. 11 is a left end view of the reducer of FIG. 9;

FIG. 12 is a right end view of the reducer of FIG. 9;

FIG. 13 is a top view of the reducer of FIG. 9;

FIG. 14 is a bottom view of the reducer of FIG. 9;

FIG. 15 is a front elevational view of a fourth embodiment of the reducer with a crimped end; the rear elevational view being a mirror image of FIG. 15;

FIG. 16 is a front perspective view of the reducer of FIG. 15;

FIG. 17 is a left end view of the reducer of FIG. 15;

FIG. 18 is a right end view of the reducer of FIG. 15;

FIG. 19 is a top view of the reducer of FIG. 15; and,

FIG. 20 is a bottom view of the reducer of FIG. 15.

The broken lines shown in FIGS. 2, 3 6-8, 10, 11 and 16-18 are for illustrative purposes only and form no part of the claimed design.
